[57] CLAIM

The ornamental design for an automobile rearview mirror, as shown and described.

DESCRIPTION

FIG. 1 is a front elevational view of an automobile rearview mirror showing my new design as a flat mirror;

FIG. 2 is a rear elevational view;

FIG. 3 is a top plan view;

FIG. 4 is a bottom plan view;

FIG. 5 is a top plan view of an automobile mirror showing a second embodiment of my new design as being slightly convex, it being understood that the front and rear elevational views are essentially like those shown in FIGS. 1 and 2 with the exception of the convexity;

FIG. 6 is a bottom plan view of FIG. 5;

FIG. 7 is a left side elevational view of FIG. 1;

FIG. 8 is a right side elevational view of FIG. 1;

FIG. 9 is a left side elevational view of FIG. 5; and,

FIG. 10 is a right side elevational view of FIG. 5.
